Design Patented, Oct. 6, 1843
No 10

Des. 10

James Albro of Elizabethtown, New Jersey,
Letters Patent No. 10, dated Oct 6th 1843

The Schedule referred to in these Letters Patent and making part
of this same. —

To all whom it may concern: —

Be it known that I, James Albro, Jr. of Elizabeth Town,
in the County of Essex, and State of New Jersey, have invented
and produced a new and original design for the printing of
Floor oil cloth, and I do hereby declare that the accompanying
drawings are full and exact representations of the same, which
I claim as my invention, and desire to secure by letter patent, not
confining myself to the size or colours of the accompanying draw-
ings. I would state that the way in which these the de-
sign is in printing it (in the usual way) with blocks, that are
sixteen inches, squares, cut into four, measuring eight to
an inch, each, four corresponding to a space made by the crossing
of the printed lines on the paper containing the drawings; the
printed cross lines, making one part of my claim.
